UNITED STATES PATENT OFFICE

JOHN W. LESLIE, OF EVANSTON, ILLINOIS, ASSIGNOR TO SIGNODE STEEL STRAPPING COMPANY, OF CHICAGO, ILLINOIS, A CORPORATION OF DELAWARE

PACKAGE STRAPPING SEAL-JOINTS

Application filed March 9, 1931. Serial No. 521,166.

My invention relates to package strapping seal-joints.

It relates particularly to seal-joints especially adapted for joining together two metal straps or overlapping portions of one strap employed to reenforce or tie a wide variety of packages, such as boxes, bales and the like.

Heretofore such seal-joints ordinarily have been produced by embracing the overlapping strap portions with a metal sleeve and then simultaneously deforming the sleeve and strap in various ways so as to bring about a separation resisting relationship between the sleeve and overlapped strap portions. Attempts have been made to produce the seal-joints without using the embracing sleeve but such sleeveless joints have been open to one or more of the following objections. Excessive power is required to produce them; in order to possess much strength it is necessary to make them too long for general application (particularly objectionable on small packages); they have not been as flat as is desirable; their formation tends to weaken the strap where it should be the strongest; there is an undesirable limitation in the sizes of strap which can be formed into such joints; and the tools required to produce them have been unduly complicated.

One of the objects of my invention is to provide an improved seal-joint for securing together overlapping portions of package binding and banding strap.

Another object is to provide an improved sleeveless joint.

Another object is to provide a joint which can be quickly and easily made.

A further object is to provide a joint which is relatively short, flat and strong.

Another object is to provide a joint which can be produced in a wide variety of strap widths.

Another object is to provide a joint which can be made by a tool of relatively simple and inexpensive construction.

Another object is to provide a joint which does not materially weaken the adjoining strap.

A further object is the provision of a new

method by which such a seal-joint may be made.

Other objects and advantages will herein-after appear.

An embodiment of my invention is illustrated in the accompanying drawings, wherein

Fig. 1 is a top or front plan view of an improved sleeveless seal-joint interconnecting two strap ends;

Fig. 2 is a bottom plan view;

Fig. 3 is a longitudinal section on the line 3—3 of Fig. 1;

Fig. 4 is a cross section on the line 4—4 of Fig. 1;

Fig. 5 is a perspective section on the line 5—5 of Fig. 3;

Fig. 6 is a perspective view of two portions of strapping positioned in overlapping relation for illustrating the first step of the method of forming my improved seal-joint;

Fig. 7 is a section on the line 7—7 of Fig. 6;

Fig. 8 is a view similar to Fig. 6 but showing the edges of the strapping material partially bent inwardly, illustrating a further step in the process of forming the joint;

Fig. 9 is a section on the line 9—9 of Fig. 8;

Fig. 10 is a perspective view of portions of strapping at a later stage in the production of the joint;

Fig. 11 is a section on the line 11—11 of Fig. 10.

Fig. 12 is a top plan of a modified type of seal-joint embodying my invention;

Fig. 13 is an enlarged perspective view of the mid-portion of the modified joint; and

Fig. 14 is a cross section on the line 14—14 of Fig. 12.

Referring first to Figs. 1 to 5 inclusive, the finished seal-joint preferably comprises two overlapping portions of metal strapping 8 and 9, the longitudinal margins of which are tightly folded inwardly toward the package

and laterally toward each other and one or more abrupt indentations or deformations 10, preferably extending inwardly from the outer or top surface of the folded strap portions, which provide interengaging offset lugs or edges, the interlocking of which prevents longitudinal separation and which are re-

tained in proper interlocking relationship by the action of the folds.

The strapping may have a slight initial curvature, if desired, to facilitate the bending or folding operations to which it is subjected in the formation of the joint, although such initial curvature is not essential to the successful formation of a seal-joint of this type.

- 10 In the production of the joint both of the straps, in a localized or restricted region, are downwardly or inwardly and laterally bent or folded along their margins as successively indicated in Figs. 9 and 11 and the depressions 10 are formed in the upper or outer surface of the strap portion 8 whereby the lugs 11 are struck inwardly therefrom, as better indicated in Figs. 3 and 5. These depressions may be so abrupt and deep as to transversely slit the metal. The formation of these lugs depresses portions 12 of the inner or under strap portion 9 and thereby form depressions or openings in the inner strap portion, the lateral edges of which constitute interlocking shoulders or edges 13 which engage shoulders or edges 14 formed by the offset ends of the lugs 11.

Fig. 10 shows one of the intermediate stages in the formation of the seal-joint which is not yet quite completely folded wherein the depressed lugs 11 have not assumed their final position, as in Fig. 4. Referring again to Figs. 4 and 5, the edges of the inner strap are slightly spaced as indicated at 15 and the edges 16 of the outer strap portion substantially envelop the inner portion and are firmly pressed thereon with such force that the inner strap portion is tightly folded upon itself as indicated at 17, leaving very small spaces, if any, at 18, where the edges of the inner portion are rebent upon themselves.

Between the depressed element 11, the intermediate portion 21 of the inner strap is retained substantially in its original position to support and reinforce the shoulders 13 in firm engagement with the shoulders 14 on the elements 11. Similarly, portions 22 outside of the depressed lugs are retained in substantially the original position, thereby aiding in the formation of a plurality of complementary interlocking relatively depressed and elevated portions spaced along the longitudinal axis of the joint.

The lugs 11 are preferably spaced substantially along the longitudinal axis of the seal and serve the purpose of transferring tensile stress from one strap portion to the other. The substantially edge to edge engagement between these lugs or tongues and the ends of the depressions in the inner or lower strap portion constitutes the principal tension resisting components of the joint. They also prevent relative longitudinal movement of the strap portions 8 and 9, which movement would otherwise cause the inner

strap 9 at the curved portion 35 (see Fig. 2) to wedge apart the similarly curved portion 36 of the strap 8 and open the joint laterally as well as longitudinally. And the opening or unfolding of the joint laterally would seriously reduce the effectiveness of the edge to edge engagement heretofore mentioned. Thus the folding of the overlapping strap portions and the interlocking of the offset edges of the deformations therein cooperate to insure a strong and lasting seal-joint; each contributes materially to the proper functioning of the other. The lugs may be so abruptly and deeply indented as to be transversely severed or sheared from the body of the outer strap portion. Preferably, however, they remain integral with the body of the strap along their outer longitudinal edges. By this construction the lugs are exceedingly rigid and strong. The mid portions of the lugs are held against twisting because of the support afforded by the tightly engaging depressed portions 12 of the inner strap and by the edges or shoulders 13 against which they laterally abut. In this manner the tensile strength of the joint is greatly increased.

Figs. 12 to 14 illustrate a modified type of seal-joint wherein the deformations to provide the edge to edge interlocking shoulders in the overlapping folded strap are located in the lateral margins of the strap in the folded region. In this modified construction the outer or top strap portion 8' and the inner or bottom strap portion 9' are folded together substantially in the manner heretofore described. The lugs or projections 11' are struck from the opposite margins of the interfolded strap and preferably bent inward or downward toward the package so as to provide, at the transverse marginal slits therein, edges or shoulders 14' which are offset so as to abut the complementary edges or shoulders 13' of the depressions or slot-like openings in the inner strap portion.

The action of the coating elements of this modified joint are essentially the same as the action of the corresponding elements of the joint heretofore described. The primary function of the tightly interfolded strap sections is to insure the proper edge to edge engagement or interlock between the relatively offset elements of the overlapping strap portions and the major function of those offset elements is to resist the longitudinal strain in the strap and prevent the joint from opening longitudinally or in the direction of that strain.

It will be understood by those skilled in the art that various changes may be made in the construction illustrated in the accompanying drawings without departing from the spirit of the invention and I therefore desire to avail myself of such modifications as

come within the scope of the appended claims.

I claim as my invention:

1. The method of seal-joining overlapping portions of metal straps which consists in deforming the same by tightly folding together the edges and forming complementary interlocking edge to edge abutting shoulders in the strap portions in the folded region.

10 2. The method of seal-joining overlapping portions of metal straps which consists in locally deforming the overlapping portions by tightly folding together the edges thereof and forming transverse complementary interlocking edge to edge shoulders in the strap portions in the folded region.

15 3. A seal-joint comprising overlapping metal straps, portions of said straps being laterally folded together so that the edges of one strap are folded back against that strap and the other strap tightly embraces the first mentioned strap, and said straps being deformed in the folded region to provide edge to edge abutting shoulders lying transversely of the straps.

20 4. A strap seal-joint comprising two overlapping strap portions, said strap portions being laterally folded together throughout a part of their lengths so that the inner strap portion is folded upon itself and the outer strap portion embraces the inner strap portion and said strap portions being deformed to provide a plurality of sets of edge to edge shoulders which interlock transversely to the direction of the length of the strap portions.

25 5. A seal-joint for strapping comprising two overlapping portions of metal strap forming the seal, one portion having a length of its edges rebent into substantially abutting relation, and the other portion having a length of its edges bent to embrace the first said portion and pressed flatwise thereupon, and a plurality of longitudinally spaced sets of laterally extending edge to edge interlocking shoulders on the said strap portions.

30 6. A seal-joint for metal strapping comprising two overlapping portions of strap locally folded together laterally into a tight flat relationship, the strap portions having tongues struck therefrom in the folded region, the tongue struck from the outer strap portion being offset to make edge to edge contact with the lateral edges of the inner strap portion where the tongue is struck therefrom.

35 7. A seal-joint for uniting overlapping straps comprising two metal straps positioned in overlapping relation, marginal portions of one strap being locally return bent and compressed flatwise and firmly upon that strap, marginal edges of the other strap extending around and being return bent flatwise and snugly upon the bent portion of first mentioned strap and an offset lug on one strap extending integrally with that strap

laterally and into the plane of the other strap to effect an edge to edge interlock therewith.

8. A seal-joint for metal strapping comprising two overlapping metal straps, portions of the margins of said straps being conjointly deformed inwardly and laterally flatwise upon the body of the straps whereby the deformed marginal portions of one strap substantially envelop the other strap, and interlocking lugs struck from the body of the straps and offset in a direction transverse to the length of the straps so as to form shoulders making contact edge to edge with the other strap.

70 9. A seal-joint for overlapping portions of metal strap comprising the overlapping portions of strap, and a lug struck from one strap portion to project into a depression in the other strap portion, the edges of the lug and of said depression constituting edge to edge interlocking shoulders transverse to the direction of strain and the overlapping strap portions being tightly folded together to prevent lateral separation and thereby retain the shoulders in interlocking relation to resist longitudinal strain.

75 10. A strapping seal-joint comprising overlapping strap portions, and a projection struck from one of the strap portions and extending into a depression which it forms in the other strap portion, the lateral edges of the projection and the lateral margins of said depression constituting interlocking shoulders which resist longitudinal separation of the overlapping strap portions and the overlapping strap portions being tightly folded together laterally of their length, such folding serving to insure the interlock between said shoulders.

80 11. A strapping seal-joint comprising overlapping strap portions having their edges in a restricted region tightly and flatly folded inwardly and laterally toward each other and the outer portion embracing the inner portion, and a lug depressed inwardly from the outer strap portion into a depression in the adjacent surface of the inner strap portion, the lateral edges of the lug and depression forming interlocking abrupt shoulders which resist longitudinal relative movement between the overlapping strap portions and which are retained in such interlocking relationship by the strap folds.

85 12. A strapping seal-joint comprising overlapping strap portions having their edges in a restricted region tightly and flatly folded inwardly and laterally toward each other and the outer portion embracing the inner portion, and a projection struck from one portion and extending into a complementary depression in the other portion, the lateral edges of the lug and depression being relatively offset to form edge to edge engagement therebetween and thereby resist strain longitudinal of the strap portions, the folded con-

dition of the strap portions serving to retain the edge to edge engagement between the edges of the lug and depression.

13. A strapping seal-joint comprising overlapping strap portions, one portion having a lug struck therefrom toward the other portion, said lug along its outer ends being integral with its strap portion but sheared therefrom along lines transverse of the strap

19. portions and projecting into a recess in the other strap portion, its sheared edges interlocking with complementary edges of said recess to resist longitudinal separation of the overlapping strap portions, and the overlapping strap portions being tightly and flatly

15. folded together in a restricted region to retain the interlocking relationship between said lug and recess edges.

14. A seal-joint comprising overlapping strap portions, opposite edges of which are crimped inwardly to provide interlock between the portions, the overlapping deformed portions being provided with a transverse slit, the metal on either side of the slit being relatively displaced to provide interlock opposing longitudinal separation.

15. A seal joint comprising overlapping strap portions, opposite edges of which are crimped inwardly so that one strap portion 30 envelopes the other to resist lateral separation, the overlapping deformed portions being provided with a transverse slit, the metal on either side of the slit being relatively displaced to provide interlock resisting longitudinal separation.

16. A seal-joint comprising overlapping strap portions, opposite edges of which are crimped inwardly over a substantial length to provide interlock between the portions, 40 the overlapping portions being provided at a location substantially within the deformed portion, with a transverse slit, the metal on either side of the slit being relatively displaced to provide interlock opposing longitudinal separation.

In witness whereof, I hereunto subscribe my name this 4th day of March, 1931.

JOHN W. LESLIE.
